(57) **CLAIM**

I claim the ornamental design for a single control button for an article of clothing, as shown and described.

DESCRIPTION

FIG. 1 is a front perspective view of a single control button for an article of clothing showing my new design.

FIG. 2 is a front view of the button shown in FIG. 1.

FIG. 3 is a left side view of the button shown in FIG. 1.

FIG. 4 is a right side view of the button shown in FIG. 1.

FIG. 5 is a top view of the button shown in FIG. 1; and,

FIG. 6 is a bottom view of the button shown in FIG. 1. Any broken line showing of the environment is for illustrative purposes only and forms no part of the claimed design.
